DESIGN FOR A DISPLAY STAND

Mordecai H. Stephens, Fort Wayne, Ind.

Application May 27, 1938, Serial No. 77,437

Term of patent 7 years

To all whom it may concern:

Be it known that I, Mordecai H. Stephens, a citizen of the United States, residing at Fort Wayne, in the county of Allen and State of Indiana, have invented a new, original, and ornamental Design for Display Stands, of which the following is a specification, reference being had to the accompanying drawing, forming part thereof.

I claim:

The ornamental design for a display stand, as shown.

MORDECAI H. STEPHENS.
